UNITED STATES PATENT OFFICE

LEO COHN, OF LOS ANGELES, CALIFORNIA

DESIGN FOR A WATCHCASE

Application filed January 16, 1931. Serial No. 38,333. Term of patent 14 years.

To all whom it may concern:

Be it known that I, LEO COHN, a citizen of the Republic of Russia, and a resident of Los Angeles, in the county of Los Angeles and State of California, have invented a new, original, and ornamental Design for a Watchcase, of which the following is a specification, reference being had to the accompanying drawing, forming a part hereof.

I claim:

The ornamental design for a watch case, as shown.

LEO COHN.
